UNITED STATES PATENT OFFICE.

EDWARD WAGNER, OF ST. LOUIS, MISSOURI, ASSIGNOR TO THE MODEL BOTTLING MACHINERY COMPANY, OF SAME PLACE.

DESIGN FOR A BOTTLE-HOLDER.

SPECIFICATION forming part of Design No. 35,063, dated September 10, 1901.

Application filed April 10, 1901. Serial No. 55,254. Term of patent 14 years.

To all whom it may concern:

Be it known that I, EDWARD WAGNER, a citizen of the United States, residing at St. Louis, in the State of Missouri, have invented and produced a new and original Design for 5 Bottle-Holders, of which the following is a specification, reference being had to the accompanying drawings, forming part thereof.

Figure 1 is a perspective view of a bottle-holder, showing my new design. Fig. 2 is a side view of a bottle-holder, showing my new design when viewed from that direction; and Fig. 3 is a front view of the same.

As shown in the drawings, this design consists in the shape or configuration imparted to a bottle holder or support. This shape or configuration consists of the combination of straight lines and curves, but the two run gracefully together, thereby producing an appearance almost of a succession of curves.

The bottle-holder is bifurcated, except where the two sides thereof are joined at H, and it should be understood that the parts hereinafter described are made and appear 25 in duplicate, said duplicate parts being joined by the straight piece H.

In side elevation this bottle-holder bears a resemblance to the interrogation-point of ordinary punctuation minus the dot and except that the lower part instead of being straight is curved at F and G and elongated into a straight portion extending in a slanting direction.

The top part of the holder is an arch B and C to the extent of a semicircle, one curve 35 thereof running into straight lines D and E, which again run into curves F and G and then unite to form a bay with H. This bay is straight on three sides and open on the fourth (the inner one) and extends downwardly from the point at which it is curvally connected with straight parts D and E. The three sides of this bay are formed in one plane. The arches B and C terminate in straight portions, which, if carried out, would make the 45 space inclosed thereby pear-shaped. As it is the parts A fall a little short of touching the parts D and E; but the parts A are in substantial alinement with the parts D and E, as well as with every other part of the arched 50 top part of the holder.

Having described my invention, what I claim, and desire to secure by Letters Patent, is—

A design for a bottle-holder, substantially 55 as herein shown and described.

In testimony whereof I have hereunto signed my name in the presence of two subscribing witnesses.

EDWARD WAGNER.
